E. H. RYERSON

DISH AND CUTLERY DRAINER

Filed Feb. 29, 1924

FIG. 1

FIG. 2

INVENTOR.
Eugene H. Ryerson.
BY
John C. Devrey
ATTORNEY.

UNITED STATES PATENT OFFICE.

EUGENE H. RYERSON, OF WOONSOCKET, RHODE ISLAND.

DISH AND CUTLERY DRAINER.

Application filed February 29, 1924. Serial No. 696,033.

To all whom it may concern:

Be it known that I, EUGENE H. RYERSON, a citizen of the United States, residing at Woonsocket, in the county of Providence and State of Rhode Island, have invented certain new and useful Improvements in Dish and Cutlery Drainers, of which the following is a specification.

My invention relates to a dish and cutlery drainer, of that class which comprises a main receptacle, made of wire, to receive and hold the dishes, and a supplemental compartment to receive the cutlery.

The object of my invention is to improve upon the construction of drainers of the class above referred to, and more particularly to provide a supplemental compartment for the cutlery, which is a part of and integral with the main receptacle for the dishes, and is contained within the main receptacle and forms a part thereof, by combining with the main receptacle a hinged divisional wall or section located within the main receptacle and pivotally hinged at its lower edge and adapted to be moved inwardly from the end of the main receptacle, to make, with the end wall of the main receptacle a supplemental compartment, of V shape in cross section, to receive the cutlery.

When the cutlery compartment is not in use the hinged divisional wall is moved against the end of the main receptacle, leaving the main receptacle of its full size and capacity.

My invention consists in certain novel features of construction of my drainer, as will be hereinafter fully described.

Referring to the drawing:

Fig. 1 is a plan view of a drainer of my improved construction.

Fig. 2 is a side view of the drainer, looking in the direction of the arrow, Fig. 1. The dotted lines show the movable divisional wall in its inoperative position.

In the accompanying drawing, 1 is the main receptacle or compartment of the drainer, to receive the dishes, which is made of open work wire, in the form of a tray, having upwardly and outwardly inclined side walls 2, and end walls 3, and longitudinally extending rods 4, and cross rods 5. Some of the longitudinal rods 4 are provided with upwardly extending V shaped

projections (see Fig. 2), to support the dishes in an upright position, all in the usual and well known way.

I will now describe my improved construction of the drainer.

At one end of the drainer, and preferably extending transversely across the drainer at one end, is a divisional wall 6, made of wire, and consisting in this instance of two longitudinally extending rods 6', at the top and bottom, and vertically extending rods 6'' between said rods 6'. The divisional wall 6 is pivotally attached or hinged at its lower edge to one of the transverse rods 5, so as to have a swinging or pivotal motion away from the end of the receptacle 1, as shown by full lines Fig. 2, and towards and against the end of the receptacle 1, as shown by dotted lines in Fig. 2.

The inward swinging motion of the divisional wall 6 is limited by the engagement of the projecting ends 6''' on the upper rod 6' of the division 6, which in this instance are made loop shape, with the top side rod or rail on the main receptacle 1. When the hinged divisional wall 6 is moved inwardly, as shown by full lines in Fig. 2, a V shaped supplemental compartment 7 (see Fig. 2,) is made, between the end wall of the main receptacle 1, and the hinged divisional wall 6, to receive the cutlery and keep it separated from the dishes in the main receptacle 1.

When it is not desired to use the supplemental compartment for the cutlery, the hinged divisional wall 6 is moved towards the end of the main receptacle, as shown by broken lines in Fig. 2, leaving the whole of the main receptacle for use as a dish drainer, if desired.

The advantages of my improved construction of a drainer will be readily appreciated by those skilled in the art. It is of very simple construction, and the supplemental compartment for the cutlery is a part of and integral with the main receptacle for the dishes. The hinged divisional wall is adapted to be moved into an inoperative position, against the wall of the main receptacle, so as not to interfere with the packing of the receptacles, one within the other, in shipping the same, thus requiring less space.

It will be understood that the details of construction of my improvements in drainers may be varied if desired.

I have shown the hinged divisional wall 5 at one end of the main receptacle, but if preferred it may be located at one side of the main receptacle.

Having thus described my invention, what I claim as new and desire to secure by 10 Letters Patent is:

1. A dish drainer for dishes and cutlery, comprising a main receptacle for the dishes, and a hinged divisional wall located within the main receptacle and adapted to be moved, to make, with the wall of the main receptacle, a supplemental compartment 5 for the cutlery, which is a part of and integral with the main receptacle.

2. In a drainer for dishes and cutlery, the combination with a main receptacle, of 20 a divisional wall, located within the main receptacle, and adapted to be moved to make a supplemental compartment for the cutlery within the main receptacle, and also to be moved against the side of the receptacle. 25

3. In a drainer for dishes and cutlery, the combination with a main receptacle, of 30 a divisional wall, located within the main receptacle, and adapted to be moved to make a supplemental compartment for the cutlery within the main receptacle, and provided with means for limiting such movement, and adapted to be moved against the end wall of the main receptacle, to leave said receptacle its full size and capacity.

EUGENE H. RYERSON.
